UNITED STATES PATENT OFFICE.

MICHELE SAVIO, OF TURIN, ITALY.

RECIPROCATING ENGINE.

1,260,816.

Specification of Letters Patent. Patented Mar. 26, 1918.

Application filed December 17, 1915. Serial No. 67,425.

To all whom it may concern:

Be it known that I, MICHELE SAVIO, a subject of the King of Italy, and resident of Turin, Italy, have invented certain new and 5 useful Improvements in Reciprocating Engines, of which the following is a specification.

This invention relates to automatic distributors intended to control the admission 10 and exhaust of the operating fluid into and from the cylinders of reciprocating engines, particularly in engines driving air compressors or water pumps which require to have no outwardly projecting members.

15 The annexed drawings show by way of example some constructions of the distributor according to this invention. Figure 1 is a central section of one construction, the piston being at an intermediate point of its 20 stroke; Fig. 2 is a central section, the piston being at one end of its stroke; Fig. 3 is the central section of a modified construction the engine piston being at one end of its 25 stroke; Fig. 4 is the central section of the same the piston being at an intermediate point of its stroke; Fig. 5 is a transverse section on X—X, Fig. 3.

As shown in Figs. 1 and 2, the head 1' of 30 the engine cylinder 1 is provided with the distributor casing 2 to which lead duct 3 feeding the operating fluid, ducts 4 and 5 each admitting into and discharging from the opposite ends of the cylinder said fluid, exhaust duct 6 and finally an auxiliary duct 35 7' having a port 7 near to end of cylinder opposite to head 1', said port being cleared by piston 13 at the end of its stroke.

In the casing 2 is arranged the reciprocating distributor 8 having partitions forming chamber 4', 5', 6', in connection with 40 the wall of said casing and provided with a head 8' sliding in chamber 2'.

The end of distributor 8 adjacent to the cylinder head 1' carries a tail 9 projecting 45 into cylinder 1, and in the front wall of chamber 2' is provided a valve 10 arranged in chamber 10' and having a stem 10'' projecting into chamber 2'. This valve controls the communication between duct 7' and 50 duct 7'' connecting chambers 2' and 10' being normally closed, while on the contrary it is raised when the head 8' occupies the position shown in Fig. 1 as the valve stem 10'' bears on said head. Thus the fluid 55 can reach the chamber 2' through duct 7' only during the interval between clearing

of port 7 by piston 13 and the end of the stroke of the distributor 8 caused by the fluid coming in the chamber 2' through the duct 7'. 60

For balancing the fluid pressures acting on partitions carried by the distributor 8 a chamber 11 is provided, this chamber communicating with the feeding duct 4 by the passage 11' and with space 2'' inclosed between the distributor and bottom of its casing by means of passage 11''; said chamber 11 is controlled by a return valve 12 allowing the fluid to pass from duct 3 and chamber 11 into space 2''. 65 70

A further passage is provided leading from space 2'' to chamber 2' and having a return valve inserted therein; this passage may be conveniently provided in the stem of distributor 8 as shown in Fig. 1, and comprises ports 14', duct 14 and a return valve 14'' allowing the fluid to pass from space 2'' to chamber 2'. 75

In this manner when the distributor 8 moves away from the position shown in Fig. 1 to assume the position of Fig. 2 under the action of the fluid under pressure reaching the chamber 2' through the duct 7', no resistance is caused by the fluid in the space 2'' as said fluid can pass in chamber 2' 80 through hole 14', duct 14 and valve 14'' raised by it. On the contrary when the distributor 8 is moved away from the position shown in Fig. 2 under the action of piston 13 on its tail 9, the fluid under pressure fed to chamber 2' does not prevent this motion of the distributor as said fluid can pass in the space 2'' through duct 11' and valve 12 raised by its pressure, so that equal 85 90 pressures exist on the opposite faces of the distributor 8. 95

The operation is as follows:—The fluid under pressure fed by duct 3 acts on lower face of the head 8' of distributor 8, said head being arranged in chamber 2', so as 100 to cause the same to take the position shown in Fig. 1. Then the fluid is admitted through port 3', chamber 4' and duct 4 into the cylinder 1 and operates the piston 13 in the direction shown by arrow in Fig. 1, 105 duct 5 communicating with exhaust duct 6 through chamber 6'.

When piston 13 is reaching the end of its stroke, the port 7 is cleared and fluid contained in the cylinder passes into duct 7' 110 and thus the valve 10 being raised by the head 8' acting on its stem 10'', comes into

chamber 2' through chamber 10' and duct 7" so as to act on the upper surface of head 8' and drive the distributor 8 into the position shown in Fig. 2.

5 At the same time the valve 10 is caused to bear on its seat by the action of the air cushion inclosed in the chamber in which its body is guided.

Then duct 4 is caused to communicate with 10 exhaust duct 6 through chamber 6', and duct 5 leading to the opposite end of cylinder 1 is connected with feeding duct 3 through chamber 5', the piston 13 being thus operated to move in the direction of arrow in Fig. 2.

15 At the end of this stroke piston 13 drives the tail 9 so as to carry again the distributor 8 in the position shown in Fig. 1, the described operation being repeated.

The pressures acting on opposite faces of 20 partitions of the distributor 8 are always balanced during reciprocations of the same as when distributor 8 is traveling from position shown in Fig. 1 into that shown in Fig. 2 the fluid acting in space 2" is exhausted

25 into chamber 2' through ports 14", passage 14 and valve 14', and when the distributor reaches said position fluid is admitted into space 2" through duct 11", chamber 11 and duct 11'.

30 The construction illustrated in Figs. 3, 4, 5, comprises a cylinder 1 provided with piston 13 and head 1' carrying the casing 2 for the distributor; this latter comprises feeding duct 3, exhaust duct 6, auxiliary duct 7' and ducts 4 and 5 leading from said casing

35 to the two ends of the cylinder. The distributing member consists of a slide 12 secured to a rod 12' having heads 8' and 8" mounted to reciprocate in chamber 2' and in casing 2 respectively. The slide 12 is intended to connect in proper succession the ducts 4 and 5 leading to the two ends of cylinder 1 with feeding duct 3 and exhaust duct 6, and the passage 7' opening into the

40 upper end of chamber 2' leads to a port 7 provided at one end of the cylinder as above described.

The lower head 8" is provided with a recess 15 communicating with chamber 16 of 50 casing 2 through holes 16', and plug 17 is located in said recess, a valve 18 being seated in it so as to cause recess 15 and chamber 16 to communicate with space 2" when required. The valve 18 is normally forced 55 against its seat by a spring 19 and is operated by tail 9 projecting into cylinder 1 and having a flange 20 intended to bear against the lower surface of plug 17 in order to raise the same and slide 12 connected therewith as a whole.

A passage 21 is provided between space 2" and exhaust duct 6, this passage having an area less than that of valve passage.

The operation is as follows:—The fluid is 65 fed through duct 3 and port 3' into chamber

16 of casing 2 and raises head 8' together with slide 12 in the position shown in Fig. 4, said slide connecting duct 5 with exhaust passage 6 and duct 4 being fed with fluid from chamber 16. The piston is thus operated in the direction of the arrow and when the same is reaching the lower end of its stroke it clears port 7, fluid being thus enabled to pass into duct 7, and to act on the upper surface of head 8' so as 70 to drive the same and slide 12, for said upper surface has a larger area than lower one, and there is no counter-pressure in chamber 2" as the same is connected with exhaust duct 6 by passage 21. The slide 12 being 75 thus carried into the position shown in Fig. 3, the upper chamber of the cylinder is connected with the exhaust duct 6 through passage 4 and slide 12, and fluid is caused to act on the lower face of piston 13 through 80 port 8, chamber 16 and duct 5, said piston being thus operated in the direction of the arrow in Fig. 3. The slide valve 12 and piston-head 8' are unable to be raised by unbalanced pressure acting in the chamber 16 during the time in which the port 7 and passage 7' are in communication with the upper chamber of the cylinder and with the exhaust duct, as the rate of exhaust from the passage 7' is slow, and the port 7 is quickly 85 closed by piston 13 immediately the same begins its reciprocation, said port 7 being then in communication with the lower chamber of the cylinder in which the fluid under pressure is fed by duct 5.

90 On the piston 13 reaching the upper end of its stroke it impinges tail 9 so as to open valve 18 thus causing fluid to pass into space 2" and balance partially the pressure acting on upper face of the head 8' and finally 95 drives said head 8" and slide 12 by the flange 20 and carries again the slide 12 into position shown in Fig. 4, the described operation being thus repeated.

The balancing valve 18 has been described 100 in connection with a slide distributor by way of example only as it may be used with a cylindrical distributor as shown in Figs. 1 and 2, as well as a slide distributor may be used in connection with the balancing arrangement shown in Figs. 1 and 2.

110 What I claim as my invention and desire to secure by U. S. Letters Patent is:—

1. In fluid engines, a cylinder, a piston reciprocating therein, a casing provided with 115 fluid feeding and exhausting ducts on said cylinder, passages leading from the two ends of said cylinder to said casing, a member reciprocating in said casing, means on said member to cause said passages and ducts to 120 communicate in proper succession, a piston head on one end of said member, a chamber in which said piston head reciprocates this chamber communicating with the fluid feeding duct, an auxiliary duct leading from one 125

- end of the cylinder to said chamber and opening therein at the opposite side of the piston head, a guiding head on the opposite end of said reciprocating member having means actuated by the piston to drive said member, means for feeding compressed fluid in the space between the bottom of said casing and said guiding head on said reciprocating member being driven by the piston, and means for discharging said fluid.
2. In fluid engines, a cylinder, a piston reciprocating therein, a casing provided with fluid feeding and exhausting ducts on said cylinder, passages leading from the two ends of said cylinder to said casing, a member reciprocating in said casing, means on said member to cause said passages and ducts to communicate in proper succession, a piston head on one end of said member, and chamber in which said piston head reciprocates, this chamber communicating with the fluid feeding duct, an auxiliary duct leading from one end of the cylinder to said chamber and opening therein at the opposite side of the piston head, a guiding head on the opposite end of said reciprocating member having means actuated by the piston to drive said member, means on said guiding head for feeding compressed fluid between the same and the bottom of the casing on said reciprocating member being driven by the piston and means for discharging said fluid.
3. In fluid engines, a cylinder, a piston reciprocating therein, a casing provided with fluid feeding and exhausting ducts on said cylinder, passages leading from the two ends of said cylinder to said casing, a member reciprocating in said casing, means on said member to cause said passages and ducts to communicate in proper succession, a piston head on one end of said reciprocating member, a chamber in which said piston head reciprocates, this chamber communicating with the fluid feeding duct, an auxiliary duct leading from one end of the cylinder
- to said chamber and opening therein at the opposite side of the piston head, a guiding head on the opposite end of said reciprocating member having means actuated by the piston to drive said member, a normally closed valve in said guiding head operating to connect the fluid feeding duct with the space between said guiding head and the bottom of the casing, means for opening said valve on the reciprocating member being driven by the piston and means for exhausting said fluid.
4. In fluid engines, a cylinder, a piston reciprocating therein, a casing provided with fluid feeding and exhausting ducts on said cylinder, passages leading from the two ends of said cylinder to said casing, a member reciprocating in said casing, means on said member to cause said passages and ducts to communicate in proper succession, a piston head on one end of said reciprocating member, a chamber in which said piston reciprocates, this chamber communicating with the fluid feeding duct, an auxiliary duct leading from one end of the cylinder to said chamber and opening therein at the opposite side of the piston head, a guiding head on the opposite end of said reciprocating member, a normally closed valve in said guiding head operating to connect the fluid feeding duct with the space between said guiding head and the bottom of the casing, a tail projecting from said valve into the cylinder to be operated by the piston, means on said tail intended to engage the guiding head to drive the reciprocating member after opening of said valve, and means for exhausting said fluid.

Signed at Turin, Italy, this 27th day of November, A. D. 1915.

MICHELE SAVIO.
